UNITED STATES PATENT OFFICE.

GEORGE A. VROOMAN, OF IRVINGTON, NEW YORK.

FOOT-SUPPORT.

1,215,891.

Specification of Letters Patent. Patented Feb. 13, 1917.

Application filed June 14, 1915. Serial No. 33,944.

To all whom it may concern:

Be it known that I, GEORGE A. VROOMAN, a citizen of the United States, residing at Irvington-on-Hudson, in the county of Westchester, State of New York, have invented 5 certain new and useful Improvements in Foot-Supports; and I do hereby declare the following to be a full, clear, and exact description of the invention, such as will enable others skilled in the art to which it 10 pertains to make and use the same.

This invention relates to new and useful improvements in inner soles for shoes and is particularly directed to the provision of an 15 inner sole for resiliently supporting the foot and for serving as a brace for the arch of the foot.

It is primarily an object of the invention to provide an inner sole for shoes whereby 20 upon walking, a current of air will be created in the shoe upon each step taken by the wearer, to avoid an excess of perspiration whereby the feet may be kept in a healthy condition, it being more specifically an object to provide such an inner sole which 25 serves also to give a resilient action which takes up the shock and promotes ease in walking and which may serve further as a support for the arch of the foot.

30 It is further an object to provide such a device which may be made of metal so as to prevent dampness from permeating to the foot of the wearer and further so as to conduct to a simple structure which may be 35 cheap to manufacture.

With these above and other objects and advantages in view, the invention resides more particularly in the novel combination, formation and arrangement of parts as more 40 fully described hereinafter and pointed out in the appended claims.

Reference is had to the accompanying drawings, wherein similar characters of reference designate corresponding parts 45 throughout the several views, and in which:

Figure 1 is a side elevation of the improved inner sole.

Fig. 2 is a bottom plan view of the inner sole.

50 Fig. 3 is a longitudinal sectional view on the line 3—3 of Fig. 2.

Fig. 4 is a cross sectional view taken on the line 4—4 of Fig. 2.

55 Referring now particularly to the accompanying drawings, the body portion of the inner sole comprises a plate 5 shaped in plan

to conform to the shape of the wearer's foot, and provided with depressions 6 and 7, respectively seating the ball and heel portions of the foot. One side of the instep portion 60 of the plate is bent upwardly at 8 to support the arch of the foot, and in the case of persons having weak arches this intermediate portion of the plate may be bent as desired to properly support the same. To promote 65 a free circulation of air the plate is provided along its side with a series of perforations 9 and the top face of the plate is provided with a facing 10 of leather, similarly perforated, and secured by bending its side 70 edges around the edges of the plate and securing them as by gluing.

A leaf spring 11 is disposed longitudinally on the bottom face of the plate and is intermediately secured by a rivet member 12 75 passing therethrough and through the adjacent instep portion of the plate. This spring is bowed on each side of its securing point and these bowed portions thus lie under the ball and heel portions of the plate, 80 with their free ends slidably bearing against the plate.

Auxiliary spring means for bracing the spring 11 comprises a spring section 13 intermediately secured on the bottom of the ball portion of the plate and having its ends bowed outwardly to slidably bear against the spring 11, and a similar spring section 14 which is secured on the rivet 12 between the spring 11 and the plate and has its ends outwardly bowed to also slidably bear against the main spring.

Thus, when this inner sole is positioned in a shoe the spring 11 normally urges it away from the bottom of the shoe, and upon the wearer taking a step the spring gives to seat the inner sole on the bottom of the shoe and the air previously confined between said sole and the bottom is forced around the shoe to provide a proper ventilation. Upon the shoe being lifted from the ground the sole assumes its first mentioned position.

In addition to providing for this circulation of air through the shoe, the inner sole provides a spring tread which materially promotes ease in walking. As the spring is secured at the instep portion of the sole, said instep portion is thus resiliently supported should it be desired to form the body plate somewhat flexible at this portion so that a 110 proper resilient support may be afforded the arches of the foot.

An exceeding simple structure has thus been provided which will efficiently perform the functions set forth.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or exceeding the scope of the appended claims.

What I claim is:—

- 15 1. In a device of the kind described, a plate shaped to conform to the wearer's foot and having a depression adjacent each end to provide ball and heel seats, the portion of the plate intermediate said depressions being formed to constitute an arch support, a leaf spring disposed longitudinally beneath the plate and having its central portion riveted to the arch supporting portion of the plate, said spring having its extremities resting against the plate adjacent the extremities of the latter and being provided with portions beneath the ball and heel seats bowed away from said seats, a spring section secured on the bottom of the ball portion of the plate and having its ends bowed
- 20
- 25
- 30

downwardly to bear against the spring, and a second spring section fixed between the plate and spring at the riveted portions thereof and having its ends bowed downwardly to engage the spring beneath the ball and heel portions of the plate respectively.

2. In a device of the kind described, a plate shaped to conform to the wearer's foot and having a depression adjacent each end to provide ball and heel seats, the portion of the plate intermediate said depressions being formed to constitute an arch support, a leaf spring disposed longitudinally beneath the plate and having its central portion riveted to the arch supporting portion of the plate, said spring having its extremities resting against the plate adjacent the extremities of the latter and being provided with portions beneath the ball and heel seats bowed away from said seats, and spring means between the plate and first spring secured to the plate beneath the ball and arch supporting portions and bearing against the first spring.

In testimony whereof, I affix my signature, in the presence of two witnesses.

GEORGE A. VROOMAN.
